US0D1081993S

(12) **United States Design Patent** (10) Patent No.: **US D1,081,993 S**
(45) Date of Patent: ** Jul. 1, 2025

(54) **BONE FIXATION GUIDE**

(71) Applicant: **Forma Medical, Inc.**, Camp Hill, PA (US)

(72) Inventors: **Andrew Charles Davison**, Hummelstown, PA (US); **James A. Gault**, Lincoln, RI (US); **Jesse F. Doty**, Hixson, TN (US)

(73) Assignee: **Forma Medical, Inc.**, Camp Hill, PA (US)

(**) Term: **15 Years**

(21) Appl. No.: **29/883,395**

(22) Filed: **Jan. 27, 2023**

(51) LOC (15) Cl. **24-02**

(52) U.S. Cl.

USPC **D24/140**

(58) **Field of Classification Search**

USPC D24/107, 133, 140, 147, 171

CPC . A61B 17/56; A61B 17/7035; A61B 17/8685; A61B 17/8605; A61B 17/8057; A61B 17/8047

See application file for complete search history.

(57) **CLAIM**

The ornamental design for a bone fixation guide as shown and described.

DESCRIPTION

FIG. 1 is a perspective front view for a bone fixation guide showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings depict portions of the bone fixation guide that form no part of the claimed design.

1 Claim, 5 Drawing Sheets
